UNITED STATES PATENT OFFICE.

SIDNEY C. BEACH, JR., OF HUNTINGTON, WEST VIRGINIA.

GAS-BURNER.

1,283,629.

Specification of Letters Patent.

Patented Nov. 5, 1918.

Application filed January 10, 1918. Serial No. 211,248.

To all whom it may concern:

Be it known that I, SIDNEY C. BEACH, Jr., a citizen of the United States, residing at Huntington, in the county of Cabell and 5 State of West Virginia, have invented a new and useful Gas-Burner, of which the following is a specification.

The device forming the subject matter of this application is a burner, and one object 10 of the invention is to provide novel means whereby the amount of fuel delivered may be regulated with extreme accuracy.

Another object of the invention is so to construct the casing which admits the fuel, 15 that the valves controlling the supply of fuel cannot be tampered with readily.

A further object of the invention is to provide novel means for mounting the casing and the nozzle in such a way that these 20 parts may be adjusted, and so that either of them may be adjusted, to regulate the supply of air, and for other purposes.

It is within the province of the disclosure to improve generally and to enhance the 25 utility of devices of that type to which the present invention appertains.

With the above and other objects in view which will appear as the description proceeds, the invention resides in the combination 30 and arrangements of parts and in the details of construction hereinafter described and claimed, it being understood that changes in the precise embodiment of the invention herein disclosed can be made within 35 the scope of what is claimed without departing from the spirit of the invention.

In the accompanying drawings:—

Figure 1 shows in top plan, a device constructed in accordance with the present in- 40 vention;

Fig. 2 shows the structure in longitudinal section, the same being mounted in a furnace wall;

Fig. 3 is a cross section on the line 3—3 of 45 Fig. 2;

Fig. 4 is a cross section on the line 4—4 of Fig. 2;

Fig. 5 is a rear end elevation.

The numeral 1 denotes a carrier, prefer- 50 ably in the form of a tube, adapted to be mounted in a wall 2 and provided with a flange 3 engaging the outer face of the wall. The numeral 4 designates, generally, a nozzle including a cylindrical body 5 slidably 55 received in the carrier or tube 1, and a tapered discharge end 6. Supports, prefer-

ably in the form of arms 7, project rearwardly from the flange 3 of the carrier 1.

At 8 there appears a box-like casing having a transverse partition 9 of considerable thickness, the partition defining a forward compartment 10 and a rear compartment 11 in the casing 8. The casing 8 has a fuel inlet 12, communicating with the forward compartment 10. A front closure plate 14 60 co-operates with the forward end of the casing 8 and a rear closure plate 15 co-operates with the rear end of the casing. Gaskets 16 are interposed between the plates 14 and 15 and the respective ends of the casing 8. The 65 plates 14 and 15 are held in place by securing elements 17 engaging the casing. The forward closure plate 14 is supplied with a plurality of small outlet openings 18 communicating with the forward compartment 70 10. There may be any desired number of these openings 18, the openings preferably being grouped together. Needle valves, in the form of screws 19 are threaded into the partition 9. The forward ends of the needle 75 valves or screws 19 are adapted to be advanced into the outlet openings 18 of the front closure plate 14, the rear ends 20 of the needle valves being located in the rear compartment 11. In the sides of the casing 8 and in the lateral edges of the plates 14 80 and 15, seats or notches 21 are formed. The arms 7 which project rearwardly from the carrier 1 are slidably received in the seats 21. The casing 8 is supplied at its sides 85 with outwardly extended lugs 22 into which set screws 23 are threaded, the set screws being adapted to bear on the upper edges of the arms 7. The set screws 23 form a clamping means. 95

In practical operation, fuel is supplied through the inlet 12 and enters the forward compartment 10. One or more of the needle valves 19 may be advanced, to close, wholly or in part, the openings 18 in the front closure plate 14. In this way, the amount of fuel passing out of the casing 8 through the openings 18 may be regulated. The fuel emitted through the openings 18 mingles with the air at the rear of the nozzle 4 and passes through the nozzle, with the air, in the form of a mixture, the mixture burning at the forward end of the nozzle 4. 100 105

Attention is directed to the fact that the rear ends 20 of the needle valves 19 are housed in the compartment 11, behind the rear closure plate 15. In view of the fore-

going construction, the needle valves 19 cannot be tampered with readily, but by removing the rear closure plate 15, any of the needle valves may be adjusted as occasion 5 requires.

The nozzle 4 prevents an objectionable noise, in the operation of the burner, and it is possible to shift the nozzle endwise, thereby to regulate the air space between the 10 nozzle and the casing 8, and for the purpose of positioning the discharge end of the nozzle 4 properly, so that the flame may be located as required. It is possible, also, to move the casing 8 forwardly and rearwardly 15 on the arms 7, thereby to regulate the air space existing between the casing and the rear end of the nozzle, the casing being held in adjusted position by tightening up the set screws 23 in the lugs 22 so that the set screws 20 bear on the upper edges of the arms 7.

Having thus described the invention, what is claimed is:

1. In a device of the class described, a casing having an integral intermediate partition defining front and rear compartments and provided with an inlet communicating with the front compartment; a plate for the front compartment and having an opening; means for securing the plate to the casing; a 25 needle valve adjustable longitudinally in the partition and coöperating with the opening, the rear end of the valve being housed within the contour of the casing in the rear compartment; a removable closure plate for the 30 rear compartment, the said closure plate shielding the rear end of the valve; means 35

for securing the last specified plate to the casing; a mixing means in front of the casing; and mechanism for holding the casing in spaced relation to the mixing means. 40

2. In a device of the class described, a casing having a partition defining front and rear compartments and provided with an inlet communicating with the front compartment; a closure for the front compartment 45 carried by the casing and having a plurality of openings; needle valves individually adjustable longitudinally in the partition and coöperating with the respective openings, the rear ends of the valves being housed in 50 the rear compartment; a removable closure for the rear compartment and carried by the casing, the said closure shielding the rear ends of the valves; a mixing means in front of the casing; and mechanism for holding 55 the casing in spaced relation to the mixing means.

3. In a device of the class described, a fuel-supplying casing having open notches in its sides and provided with outstanding 60 lugs disposed adjacent to the notches; clamping means carried by the lugs; and a carrier having rearwardly extended arms slidably received in the notches and engaged by the clamping means. 65

In testimony that I claim the foregoing as my own, I have hereto affixed my signature in the presence of two witnesses.

SIDNEY C. BEACH, JR.
